Attorney

UNITED STATES PATENT OFFICE.

MARIE CESKA, OF BOWDLE, SOUTH DAKOTA.

DARNER.

1,337,884.

Specification of Letters Patent. Patented Apr. 20, 1920.

Application filed September 28, 1918. Serial No. 256,070.

To all whom it may concern:

Be it known that I, MARIE CESKA, a citizen of the United States, residing at Bowdle, in the State of South Dakota, have invented 5 new and useful Improvements in Darners, of which the following is a specification.

This invention relates to darners and has for its primary object to provide a darning by means of which material may be more 10 readily darned and in a more efficient manner.

An object of the invention is to provide a darning of such a construction that the material worked upon will not be subject to 15 excessive strains which tend to dislocate or break the strands thereof.

Another object of the invention is to provide a darning that will space different parts of the material worked upon from 20 the darning so that a needle may more effectively work upon the goods without coming in contact with the darning.

Besides the above my invention is distinguished in the manner of associating the 25 body with the handle so that the material or goods may be more readily gripped and stretched across the working face of the darning for obvious reasons.

With these and other objects in view the 30 invention will be better understood from the following detailed description taken in connection with the accompanying drawing wherein:

Figure 1 is a perspective view of the 35 darning.

Fig. 2 is a side elevation partly in section of the darning showing it associated with a piece of material.

At the start I wish to call attention to 40 the fact that the darning may be made of any shape or size, therefore I do not desire to be limited to the exact showing in the drawing which shows the body 1 of the darning provided with a circular flat 45 working face 2. The body is connected to and formed integral with the handle 3 and approximately at the point of juncture of the handle 3 with the body 1, the former is reduced and curved as indicated at 4 for 50 a purpose hereinafter described.

The working face 2 is provided with an upstanding flange 5 which coöperates with a portion of the face 2 to provide a groove 6.

The flange 5 encircles a depression or 55 recess 7 in the working face 2. As far as

I have proceeded it will be seen that when the material 8 is arranged across the working face 2, different portions 9 and 10 of the material will be spaced from portions of the darning with the result that the darning can be more efficiently accomplished and the point of the needle will not come in contact with the darning. Another very important feature of my invention is the manner in which the material is held so that the needle will not have to travel in an arcuate direction when darning which is the case with the egg shaped darning now on the market. In concluding my description I wish to call attention to the manner 70 in which portions A and B of the material pass across the curved portion 4 of the body, with a result that when the same is gripped by the user, the material will be properly stretched across the working face 75 of the darning and effectively held against displacement during the darning operation.

It is of course to be understood that the darning may be gripped in any suitable manner and one efficient way of gripping the 30 darning is by passing the fingers around that reduced portion of the body 1 next to the handle. When the darning is thus gripped, the handle 3 coöperates with the bell shaped body 1 to effectually prevent slipping of the 35 device from the user's hand, and the handle also provides means whereby the body may be readily inserted into an article to be darned.

From the foregoing description taken in 40 connection with the accompanying drawing it should be apparent that I provide a device of simple substantial construction capable of more efficiently darning material than those devices now on the market. 95

Having described my invention, what I claim is:

A darning comprising a substantially bell shaped body and a handle secured to said body at the smaller end thereof and disposed substantially at right angles to the body, said body being provided with a central recess in its larger end and having an upstanding flange surrounding said recess, said flange being remote from the periphery 100 of the body and coöperating therewith to space material placed about the body away from same.

In testimony whereof I affix my signature.

MARIE CESKA.
